United States Patent

Des. 236,685
Patented Sept. 9, 1975

236,685

BOTTLE

Alan R. Tripp, New York, N.Y., assignor to Ventura
Product Development Corp., New York, N.Y.

Filed Aug. 20, 1973, Ser. No. 389,485

Term of patent 14 years

Int. Cl. D9—01

U.S. Cl. D9—56

FIG. 1

FIG. 2

FIG. 3

FIG. 4

FIG. 5

FIG. 1 is a perspective view of a bottle showing my new design;

FIG. 2 is a top plan view;

FIG. 3 is a side elevational view;

FIG. 4 is a front elevational view; and

FIG. 5 is a rear elevational view illustrating the two sides of the bottle which are identical.

I claim:

The ornamental design for a bottle, as shown and described.
